HOPPER MECHANISM FOR SLIDE FASTENER
END STOPS

Harry Levine, Brooklyn, N. Y.

Application March 6, 1948, Serial No. 13,406

4 Claims. (Cl. 153—1)

1

This invention relates to a hopper mechanism for slide fastener end stops for mounting end stops on slide fastener stringers.

It is an object of the invention to provide an apparatus of the character described in which the end stops, prior to mounting, are withdrawn from a hopper without mutilation.

It is a further object of the invention to provide an apparatus of the character described in which, during and after withdrawal from a hopper and until they are mounted on stringers, the end stops are maintained under positive positional control.

It is an additional object of the invention to provide an apparatus of the character described which comprises comparatively few and simple parts, and is rugged in construction and speedy in operation.

Other objects of the invention will in part be obvious and in part be pointed out hereinafter.

The invention accordingly consists in the features of construction, combinations of elements, and arrangement of parts, which will be exemplified in the device and process hereinafter described and the scope of which will be indicated in the appended claims.

In the accompanying drawings, in which is shown one of the various possible embodiments of the invention:

Fig. 1 is a side view of an apparatus constructed in accordance with the invention;

Fig. 2 is a front view of said apparatus;

Fig. 3 is a fragmentary sectional view taken substantially along the line 3—3 of Fig. 2, and is illustrative of the arrangement of the transfer mechanism;

Fig. 4 is an enlarged sectional view taken substantially along the line 4—4 of Fig. 1, and is illustrative of the construction of the hopper;

Fig. 5 is a fragmentary enlarged side view of the station at which end stops are introduced into the gravity chute;

Fig. 6 is a sectional view taken substantially along the line 6—6 of Fig. 5;

Fig. 7 is a vertical central sectional view through the apparatus at the transfer mechanism, the same being taken along a plane parallel to the direction in which the mechanism shifts end stops;

Fig. 8 is a sectional view taken substantially along the line 8—8 of Fig. 7;

Figs. 9 and 10 are detail sectional views taken substantially along the lines 9—9 and 10—10, respectively, of Fig. 8, the same being illustrative of the construction of pins for maintaining end

2

stops in proper position during transfer and of the means for operating said pins;

Fig. 11 is a view similar to Fig. 7 but showing the transfer mechanism and its coating parts at a different stage of operation;

Fig. 12 is a fragmentary view taken substantially along the line 12—12 of Fig. 11, the same being exempliutive of the position of the positioning pins at the time that the transfer mechanism receives an end stop; and

Fig. 13 is a perspective view of an end stop as it appears before mounting on a slide fastener stringer.

Referring now in detail to the drawings, 20 denotes an apparatus embodying the invention, the same being adapted to withdraw end stops from a mass of randomly disposed end stops and to attach them on a slide fastener stringer. End stops of the type which said machine is designed to handle are exemplified by the end stop 22 shown in Fig. 13. Said end stop is conventional and comprises a U-shaped member having a base strap 24 from whose two ends, stub arms 26, 28 extend. Each arm is bifurcated to form a pair of divergent fingers 30 on whose tips inturned nibs 32, 34 are provided for a purpose well known in the art. The arms 26, 28 are substantially perpendicular to the base 24 and the distance between the nibs 32, 34 is slightly in excess of the thickness of the beaded edge of a slide fastener stringer on which the end stop is designed to be mounted.

In general, the apparatus 20 comprises a hopper in which a loose mass of end stops disposed at random are contained, means for withdrawing end stops from the mass and arranging them in predetermined position, means for transferring end stops from the withdrawing means to a gravity chute, means to dislodge elements improperly disposed at the entrance to the chute, a transfer mechanism for shifting end stops from the lower terminal of the chute to an attaching station, means to maintain the end stops in proper position during transfer and attachment, and means to attach the end stops to a slide fastener stringer.

The hopper is denoted by the reference numeral 36 and its construction is best shown in Figs. 1, 2 and 4. Said hopper comprises a pair of hollow halves 38, 40, each of which includes a frusto-conical side wall 42 closed at its smaller end by a wall 44 carrying a centrally disposed bearing 46. Each frusto-conical wall is formed with a large opening 48 to provide a mouth for inserting loose end stops. The larger ends of

the frusto-conical wall have an outwardly extending flange 50 disposed on opposite sides of a plate 52 and around a circular opening 54 in said plate, whereby the two halves 36, 38 and said plate define an enclosure or hopper in which loose end stops are contained.

The two wall bearings 46 are arranged in alignment to rotatably receive a spider shaft 56 journaled in main bearings 58 on a frame 60 which is carried by the base 62 of the machine. The spider shaft is turned by any suitable intermittently operating means; for example, the shaft has affixed thereto a ratchet wheel 64 which is intermittently engaged by a dog 66 pivotally secured to an oscillating lever 68 swinging on the shaft 56. The lever 68 is reciprocated by a link 70 whose lower end has a yoke 72 straddling a drive shaft 74 journaled in the base 62. Said yoke supports a roller follower 76 which rides in a track cut in the side face of a cam plate 78. The plate is fixed for rotation on the drive shaft 74 and its track is so shaped that once each revolution of the drive shaft, the link 70 is pulled down and then restored to its original position, thus causing the spider shaft 56 to advance a certain angular distance determined by the throw of the dog 66. As a matter of practice, in the embodiment of the invention shown herein, this distance is equal to 45° so that the spider shaft turns through 360° once for every eight revolutions of the drive shaft. Suitable means, not shown, is employed to prevent the spider shaft from turning backwards on the retrograde stroke of the dog.

The shaft 56 carries a spider 80 comprising a plate equal in thickness to and coplanar with the plate 52. The central portion of the spider is apertured to admit the shaft 46 and carries a pair of integral collars 81 fixed to the plate, as by welding, and rigidly secured to the shaft, as by set screws. Extending outwardly from the hub portion of the plate 80 are a plurality of arms 82 which are designed to ride on the edge of the circular opening 54. The leading edge 84 of each arm is inclined at a relatively acute angle to said opening while the trailing edge 86 is inclined more steeply to said opening. The portion of the spider intermediate adjacent arms is smoothly curved, as seen in Fig. 1. This arrangement permits the leading edges to pick up the U-shaped end stops as the arms pass through the bottom of the mass of end stops in the hopper, and to transfer such end stops by sliding to the trailing edge of the preceding arm as the spider rotates. Such transfer can be seen by comparing the positions of end stops on the top four arms in Fig. 1.

The width of the plate 52 and of the spider arm is just slightly less than the distance between the two arms 26, 28 of the end stops, whereby an end stop picked up on a spider will be disposed astraddle the arm with its base strap 24 across the edge of the arm and its stub arms 26, 28 dangling down on the opposite sides of the spider arm. Such disposition of the end stops will be seen from inspection of Fig. 4.

Obviously, due to the substantial length of the leading edges 84, each time that a spider arm passes through the loose mass of end stops, one or more end stops will be picked up on the arm. These end stops are transferred from the trailing edges 86 of the spider arms to a gravity chute at a delivery station 88 (see Fig. 5).

The upper portion of the gravity chute simply consists of an inclined slot 90 in the plate 52.

The slot starts at the circular opening 54, being located above the mass of end stops in the hopper and on the side of the mass at which the spider arms descend. Said slot is arranged to be approximately in line with a trailing edge of a spider arm at the time of transfer. The intermittent operation of the shaft 56 is so timed relative to the position of the spider on said shaft and to the entry end of the gravity chute that the spider intermittently stops with a trailing edge of one of its arms aligned with the lower edge of the slot 90. Due to the position of the slot, the trailing edge aligned therewith is one which has passed through the loose mass of end stops and has one or more end stops straddling it, ready for delivery into the chute. These end stops will slide along the arm and into the chute under the influence of gravity, the chute being inclined steeply enough to permit the end stops to travel through it in like manner.

Difficulty has been experienced in the jamming and mutilation of end stops at the delivery station 88. For example, an end stop may turn slightly as it is being introduced into the chute. Such a stop may enter part way into the chute and then not slide any further due to its improper position. No end stops then could enter the chute until the improperly positioned stop is removed. Also, the chute might be filled, with just enough room left at the top of the chute to hold part of the next end stop. Such an end stop would project slightly out of the entry mouth of the chute and, when the toe 92 of the next spider arm advanced, it would hit said stop and deform it. Such deformed stop might continue to slide down the chute and subsequently would be fastened to a stringer where it would be quite likely to break and render the stringer defective. On the other hand, if the damaged end stop would not slide down the chute, it would jam the chute and have to be removed manually.

Pursuant to a feature of the present invention, means are provided in the vicinity of the delivery station for eliminating the foregoing source of trouble. Such means comprises two mechanisms, to wit: a knock-off lever 94 and a spring mounted pad 96.

The knock-off lever is in the form of an arcuate metal strip 98 whose upper end is pivotally carried by a stud 100 secured to a member 102 integral with the hopper. Said stud is so disposed that the outer end 104 of the spider arm immediately before the one at the delivery station will ride on and engage a cam projection 106 on the under edges of the lever and thereby push the lever away from the shaft 56 to such an extent that its free swinging tip 110 is slightly in back of and below the entry end of the slot 90. When the shaft next is intermittently rotated, the spider arm which descends to the delivery station, will, shortly after it starts moving, ride off the cam, thus permitting the lever 98 to descend under the influence of gravity. Since the cam is rather low, the lever will only swing a short distance but this will suffice to allow the tip of the lever to move past the delivery station and to knock out the mouth of the chute any end stop which is improperly positioned therein or which projects beyond the mouth of the chute. Before this spider arm reaches the delivery station, the spider arm which follows it will engage the cam thereby to raise the knock-off arm back to its inoperative position.

The machine works so rapidly that occasionally

the knock-off arm fails to remove from the mouth of the chute an end stop projecting very slightly beyond said mouth. To prevent mutilation of such an end stop, the pad 96 is provided. This pad comprises a block 112 captively mounted in the plate 52 in such fashion that it can slide vertically. One surface of said block forms the lower edge of the chute at the delivery station. Another surface of the block constitutes a portion of the circular opening 54. The block is resiliently biased in an upward direction by means of a spring 114 to a position in which its second mentioned surface forms part of the opening 54.

Suitable means, not shown, is incorporated to limit the upward movement of the block to the position just mentioned. If the toe 92 of a descending spider arm should strike against an end stop projecting slightly from the mouth of the delivery chute, instead of deforming the end stop, the toe merely will depress the block 112.

The inclined slot 98 runs into a vertical slot 116 formed by a pair of plates 118, 120 which constitute the lower portion of the gravity chute. This vertical slot terminates immediately above a transfer mechanism 122 designed to present one end stop at a time to a clinching station.

The transfer mechanism, which is mounted directly on the base 62, includes a slide block 124 reciprocable between a pair of gibs 126, 128 and held down by restraining plates 130. The forward portion of the block 124 has a hardened insert 132 which functions as an anvil and work holder. Said insert has its forward portion indented to provide a depressed shelf 134 whose back edge or shoulder 136 is outwardly convex. The central portion of the shelf adjacent the back edge has a recess 138 fashioned therein just large enough to slidably receive the lower portion of an end stop in the horizontal position shown in Figs. 11 and 12, i. e., with its arms pointing forwardly.

The block 124, by virtue of its mounting between the gibs, can be shifted back and forth. In the rearmost position of the block the recess 138 is directly beneath the lower end of the vertical slot 116 so that the lowermost end stop in said slot can drop into the recess, providing that the recess is empty.

Preferably, means is included to properly locate the end stop thus dropped in the recess 138 thereby preventing it from tilting out of its proper position for attachment. Such means comprises a pair of upstanding pins 140 carried by a plunger 142. In order to permit vertical adjustment of the pins, the upper part of the plunger is split, the two halves being separated by a space 146. Said halves are arcuately notched as at 146 to define split bores in which the enlarged lower ends 148 of the pins 140 are received. The two halves of the plunger 142 are clamped together by a bolt 150 having an elongated head fitted in an opening 152 of another plunger 154 near the plunger 142 so that the two plungers are tied together for joint movement. Said plungers are vertically reciprocable in wells 156, 158 respectively, these wells being interconnected by a passageway 160 to permit movement of the head of the bolt 150. The well 158 has a lateral aperture 162 to permit insertion of the tool for turning the bolt 150. A compression spring 164 is disposed in the well 158 beneath the plunger 154 so that normally said plunger is urged upwardly, such upward movement being limited by abutment of the top end of the plunger 142 against

the undersurface of the anvil 132 which caps the well 156.

The insert is provided with two vertical passageways for passing the pins 140. These passageways are so disposed that the pins engage the inner surface of the end stops adjacent the juncture between the base strap and arms 26, 28, when the outer surfaces of said arms and base strap are in sliding contact with the walls of the recess 138, whereby the end stops are disposed in proper position. Such location of the pins and the lowermost end stop is shown in Figs. 11 and 12.

The plunger 154 carries an erect stud 166 which extends through a bore in the block 124 and protrudes above the upper surface of said block. Pressing down the protruding portion of the stud 166 against the action of the spring 164 will lower the locating pins 140, and sufficient clearance is provided to enable the pins to be depressed sufficiently to bring their tips below the bottom surface of the recess 138.

Means is included to reciprocate the block 124 between its gibs. Such means, which is operated from a hollow shaft 125 rotatable on the drive shaft 74, comprises a face cam 168 fixed to said hollow shaft and engaging a roller 170 disposed at one end of a lever 172 pivoted on the underside of the base 62. The other end of the lever is bifurcated to slidably receive a pin 174 fixed to the block 124 and extending through a slot 176 in the base of the machine. Only one actuating node 178 is provided on the cam 168 in the form of the invention illustrated herein so that once each revolution of the hollow shaft 125, the block 124 will be moved from an advanced position to a position in which the recess 138 is directly beneath the vertical chute 160 position and then back to its starting position.

In the advanced position of the block 124, said recess 138 is located immediately beneath the clinching end 180 of a ram 182. Said end of the ram is adapted to be driven downwardly to press against the end stop contained in the recess 138 and clamp the divergent fingers 30 of the lugs on the beaded edge of a tape. To this end the ram 182 is slidably in a pair of journals 184 carried by the main frame 60. A pair of slots 186 are formed in the sides of the ram to receive the circularly enlarged ends 188 of rock levers 190 whose opposite ends are pivotally secured to a fitting 192 carrying a link 194. Said link is provided with a yoke 196 at its lower end which straddles the hollow shaft 125 and maintains the link in vertical position. The link carries a follower roller pin 198 which rides in a track cut in the side of a cam 200 secured to the hollow shaft 125. The cam track is so designed that once each revolution of the hollow shaft 125, it will lower the ram 182 from its elevated position (Fig. 11), down to a clamping position shown in Fig. 7, and then back to its initial position.

Means also is included to lower the locating pins 140 so as to permit withdrawal of an end stop disposed in the anvil after said stop has been clamped on a slide fastener stringer. Such means consists of a foot 202 secured to the lower end of the ram and movable therewith. The position of the foot can be vertically adjusted, said foot being provided with vertical slots, not shown, through which the shanks of bolts 204 pass, these being bolts which hold the foot to the ram. Said foot is disposed immediately above that portion of the block 124 in which the stud 166 is located at the time that the block is in its advanced po-

sition indicated in Fig. 7, and said foot is so vertically positioned that it will engage the stud and depress it just before the clamping tool 180 forced the nibs of the fingers 28 together.

The various cams 78, 168 and 200 are timed so that the machine operates in the following manner: The drive shaft 74 is turned over continually by a motor 206 so that the cam 78 continually oscillates the spider shaft 56 at intervals. However, the hollow shaft 125 normally stands idle. This shaft is clutched to the drive shaft 74 through a clutch 207 actuated by a foot treadle 208. When said treadle is depressed, the clutch 207 is rendered operable. Said clutch is constructed in any well known manner in the art, to cause the hollow shaft to turn with the drive shaft 74. Moreover, said clutch is of any well known one-revolution type, that is to say, the clutch itself is so constructed that, when actuated, it will remain engaged for one revolution of the driving and driven shafts whereby the shaft 125 will turn through one revolution with the drive shaft 74 and then automatically will be disconnected from said driving shaft. When the hollow shaft is idle, the ram 182 is raised, as shown in Fig. 11, and the transfer block 124 is in its advanced position, illustrated in Fig. 7. As soon as the treadle 208 is depressed, the cam 200 will move the ram 182 downwardly a sufficient distance to clamp the fingers of an end stop disposed in the recess 138. However, the toe 202 leads to the clamping tip of the ram so that the locating pins will be out of the way beneath the surface of the recess before the end stop is fully clamped. The cam 200 is designed to thereafter immediately raise the ram 182 a short distance, enough to permit the closed end stop to be withdrawn between the tip of the ram and the shelf 134. Such raising of the ram, however, is not sufficient to permit the tips of the locating fingers again to be thrust into the recess 138.

Next, the cams, while still holding the ram 182 partially depressed, will retract the transfer block 124, pulling the stud 166 clear of the toe 202 and thus allowing the locating pins to be restored to receiving position. The transfer block thereupon is moved to its rearmost position in order to allow the lowermost end stop in the vertical chute 116 to drop into the recess 138. Said block will rest for a short period of time at this rearmost position so as to permit the end stop to settle itself. During such time, or any time after the stud 166 has cleared the toe 202 the ram 182 is raised by the cam 209 to its uppermost position, as indicated in Fig. 11. Finally, the transfer block 124 is moved back to its advanced position and at such time the clutch 207 disengages itself.

To use the machine, an operator places the edge of a stringer between the spread fingers of an end stop located in the recess 128 and then steps on the treadle 208. The ram thereupon descends to clamp the end stop on the stringer, the locating fingers descending beneath the ram. Now, when the ram raises a short distance and the transfer block slides back, the stringer automatically will be disengaged from the anvil 132 as the operator holds the stringer taut. During the remainder of the cycle of the machine, a fresh end stop is inserted automatically and the parts repositioned to receive a new stringer.

It thus will be seen that there is provided a hopper mechanism for slide fastener end stops which achieves the various objects of the inven-

tion and is well adapted to meet the conditions of practical use.

As various possible embodiments might be made in the above invention, and as various changes might be made in the embodiment above set forth, it will be understood that all matter herein described or shown in the accompanying drawings is to be interpreted as illustrative and not in a limited sense.

Having thus described the invention, there is claimed as new and desired to be secured by Letters Patent:

1. In an apparatus for collecting and delivering end stops to a mounting machine, each said end stop including a base strap and a pair of arms: a hopper, a spider having flat arms adapted to revolve in a vertical plane about a horizontal axis through a mass of loose end stops in said hopper whereby end stops will be picked up astraddle said spider arms, means to intermittently rotate said spider, a gravity chute in said vertical plane, the upper end of said chute being adjacent the path of travel of the tips of the spider arms and below the axis of rotation of the spider, said means for intermittently rotating the spider being arranged to stop the spider intermittently with one arm after another successively in registry with the upper end of the gravity chute whereby end stops astraddle the spider arms will slide down the arm in registry with the upper end of the chute by gravity and into the chute, and means to knock off end stops jammed in or projecting from the upper end of said chute, said last-named means comprising a member mounted so that the tip thereof is movable through the path of travel of end stops entering the upper end of said chute and means to move said member through said path during only the time that the spider is intermittently rotated and in a direction opposite to that in which said stops enter the upper end of the chute so as to knock back into the hopper end stops jammed in or projecting from the upper end of the chute as aforesaid.

2. In an apparatus for collecting and delivering end stops to a mounting machine, each said end stop including a base strap and a pair of arms: a hopper, a spider having flat arms adapted to revolve in a vertical plane about a horizontal axis through a mass of loose end stops in said hopper whereby end stops will be picked up astraddle said spider arms, means to intermittently rotate said spider, a gravity chute in said vertical plane, the upper end of said chute being adjacent the path of travel of the tips of the spider arms and below the axis of rotation of the spider, said means for intermittently rotating the spider being arranged to stop the spider intermittently with one arm after another successively in registry with the upper end of the gravity chute whereby end stops astraddle the spider arms will slide down the arm in registry with the upper end of the chute by gravity and into the chute, and means to knock off end stops jammed in or projecting from the upper end of said chute, said last-named means comprising a member mounted so that the tip thereof is movable through the path of travel of end stops entering the upper end of said chute and means operable by said arms to move said member through said path during only the time that the spider is intermittently rotated and in a direction opposite to that in which said stops enter the upper end of the chute so as to knock back into the hopper end stops jammed in or

projecting from the upper end of the chute as aforesaid.

3. In an apparatus for collecting and delivering end stops to a mounting machine, each said end stop including a base strap and a pair of arms: a hopper, a spider having flat arms adapted to revolve in a vertical plane about a horizontal axis through a mass of loose end stops in said hopper whereby end stops will be picked up astraddle said spider arms, means to intermittently rotate said spider, a gravity chute in said vertical plane, the upper end of said chute being adjacent the path of travel of the tips of the spider arms and below the axis of rotation of the spider, said means for intermittently rotating the spider being arranged to stop the spider intermittently with one arm after another successively in registry with the upper end of the gravity chute whereby end stops astraddle the spider arms will slide down the arm in registry with the upper end of the chute by gravity and into the chute, and means to knock off end stops jammed in or projecting from the upper end of said chute, said last-named means comprising a member mounted so that the tip thereof is movable through the path of travel of end stops entering the upper end of said chute and a cam on said member engageable by the arms of the spider and while the arms are clear of the upper end of the chute to move said member through said path during only the time that the spider is intermittently rotated and in a direction opposite to that in which said stops enter the upper end of the chute so as to knock back into the hopper end stops jammed in or projecting from the upper end of the chute as aforesaid.

4. In an apparatus for collecting and delivering end stops to a mounting machine, each said end stop including a base strap and a pair of arms: a hopper, a spider having flat arms adapted to revolve in a vertical plane about a horizontal axis through a mass of loose end stops in said hopper whereby end stops will be picked up astraddle said spider arms, means to intermit-

tently rotate said spider, a gravity chute in said vertical plane, the upper end of said chute being adjacent the path of travel of the tips of the spider arms and below the axis of rotation of the spider, said means for intermittently rotating the spider being arranged to stop the spider intermittently with one arm after another successively in registry with the upper end of the gravity chute whereby end stops astraddle the spider arms will slide down the arm in registry with the upper end of the chute by gravity and into the chute, a pad, means mounting said pad for translatory movement in said vertical plane from a first position in which an edge thereof constitutes the lower edge of the upper end of the chute to a second position below the said first position and spring means biasing said pad toward said first-named position whereby said pad will be depressed when a spider arm presses down against an end stop jammed in or projecting from the upper end of said chute.
